INTERLOCKING SHINGLE

David B. Ronzone, Wilmington, Del.

Application April 5, 1949, Serial No. 85,638

3 Claims. (Cl. 108—17)

1

The present invention relates to a new and improved form of interlocking shingle and more particularly to an improvement over the shingle disclosed in my prior Patent 2,486,326, issued October 25, 1949.

The shingle disclosed in the aforesaid patent is particularly adaptable to shingles formed of metal but is of such construction that it can be made of composition material. The advantages of a metal shingle have long been known but due to high costs has been little used. The primary object of the present invention is to provide a metal shingle which can be manufactured at a relatively low cost, comparable to a composition shingle, and yet embody all of the advantages of a metal shingle with numerous advantages not previously shown or contemplated.

As pointed out in my patent, shingles of the interlocking type are generally formed by extending the slots inwardly from the edges of the shingle to define the locking tabs and the co-operating locking slots. This results in a number of imperfect shingles due to the fact that the tabs are easily bent or torn during the assembly operation or after the shingles have been interlocked.

This defect is overcome by the shingle of the instant case and the pending case by having the slots forming the locking tabs and the co-operating locking slots wholly within the confines of the shingle, the edge of the shingle being left continuous and uninterrupted.

In the present invention, the shingle is formed of metal and preferably of aluminum. The use of aluminum renders the shingle somewhat flexible and in order to reinforce the shingle, I have provided a novel integral rib arrangement which not only serves to reinforce the shingle but acts to interlock the shingles in such manner as to form a rigid shingle assembly. The novel rib arrangement also serves to permit the circulation of air within the shingles and yet prevent side lash from rain or wind or the seepage of rain beneath the shingles.

A further feature of the present invention is the provision of a metal shingle capable of being formed from sheet metal by a single stamping operation thereby resulting in economy of manufacture. The novel construction is such that the shingles can be assembled with a minimum amount of labor and when applied to a roof presents a most attractive appearance.

Other objects and advantages of the invention will be apparent in the following detailed description taken in connection with the accompanying drawing, wherein

2

Figure 1 is a plan view of a preferred embodiment of the shingle forming the subject matter of the present invention;

Figure 2 is a fragmentary plan view of a portion of a roof formed by laying the shingles of Figure 1;

Figure 3 is an exploded view showing the manner of assembling two adjacent shingles;

Figure 4 is an enlarged sectional view taken on the line 4—4 of Figure 2;

Figure 5 is an enlarged perspective view of several assembled shingles with a portion of one of the overlying shingles broken away to show the details of construction;

Figure 6 is a fragmentary elevational view of a roof section;

Figure 7 is a front sectional view taken on the line 7—7 of Figure 6.

Referring to the drawings in detail, Figure 1 illustrates a preferred embodiment of the invention, the shingle being formed of aluminum or equivalent sheet metal. The shingle is of generally rectangular configuration and constitutes a body portion 10 bounded by the edges 11, 12, 13 and 14. The lower edge 14 of the shingle is in the form of a down-turned flange formed during the stamping operation. The edge 11 is slightly offset from the plane of the shingle by offsetting a small portion of the shingle during the stamping operation, said offset portion being indicated by the numeral 25. At the line formed by this offset portion 25, a pair of slots 15 are stamped out of the metal shingle and constitute the locking slots. The locking tabs 16 are formed by cutting U-shaped slots in the shingle as indicated by numeral 17. The locking tabs 16 are one inch in width and the slots 15 are approximately one inch and one sixteenth wide in order to readily receive the locking tabs.

As seen in Figure 1, a pair of holes 18 are cut out of the shingle adjacent the slots 15 for receiving the usual nail 23 for attaching the shingle to a roof. An additional nail hole 19 is provided midway of the shingle adjacent the edge 12 for properly lining up the shingles during the roof assembly as will more clearly appear as the description proceeds.

In order to insure against side lash and to increase the rigidity of the shingle, the shingle is provided with a pair of parallel upstanding ribs formed in the shingle during the stamping operation. One of the ribs, designated by the numeral 20 is located adjacent the slots 15 and the second rib 21 is formed at the edge 13. The ribs 20 and 21 extend entirely across the shingle and a transverse rib 26 extends between the two ribs

20 and 21 for added rigidity and further serves as a rain stop as will be pointed out below.

The flange 14 is provided substantially midway the length thereof with a cut-out portion 24 to receive the rib 21 as seen in Figures 5 and 6. As seen in Figure 6, the height of the cut-out portion 24 is equal to the height of the rib 21 in order that the portion of the flange 14 to the right of the rib comes in close contact with the shingle below the flange. This is indicated in Figure 6 by numeral 28. The three overlapping shingles being referred to in this figure are indicated by numerals 29, 30 and 31. As seen in Figure 7, that portion of the flange 14 of the shingle 31 to the left of rib 21 and closely adjacent the rib is slightly spaced from the underlying shingle 30, as indicated at 27. This space is equivalent to the thickness of a shingle and results from an overlapping of the shingles at this point. The function of this space is to provide 20 an air circulation opening as will be pointed out below.

The shingles may be assembled in interlocked relationship in the manner shown in Figures 2 to 5 wherein the numeral 22 denotes the usual wooden roof member to which the shingles are applied. In assembling the shingles, the shingles are laid from left to right beginning at the lower left hand corner of the roof. The first shingle is laid and nails 23 driven through the holes 18. The next adjacent shingle is then applied by pressing down on locking tabs 16 and inserting said tabs through slots 15. When the overlying shingle is pushed to the right with the rib 21 overlying the rib 20, the second shingle is secured to the roof by driving nails into the second set of holes 18 of the overlapping shingle. This operation is continued until the lower row of shingles is assembled.

The first shingle of the second row is applied by juxtaposing its lower hole 18 over hole 19 of the first row shingle and continuing the assembly as previously explained. The provision of hole 19 thus insures the proper positioning of the second row of shingles. All of the rows of shingles 40 may be assembled in a similar manner.

As seen in Figure 5, the air aperture 27 permits air to enter below the shingle and thereby enables air circulation within the shingles. The flange 14 acts as a rain breaker and any seepage 45

of rain below flange 14 will be blocked by the rib 26.

Although the present embodiment of the invention is illustrated in connection with roofing shingles, it will be readily apparent that the present invention may also be applied to siding shingles.

It will be noted that the construction herein shown and described is well adapted to accomplish the objects of the present invention. It will be understood that minor changes may be made in the present invention without departing from the spirit thereof. Therefore, I do not wish to be limited precisely to the construction herein shown except as may be required by the appended claims considered with reference to the prior art.

I claim:

1. An interlocking shingle comprising a body portion of general rectangular configuration having a forward edge, transverse edges and a rear edge, a portion of the shingle adjacent said forward edge being upwardly offset, locking slots formed at the juncture of said offset portion and the remainder of the shingle, cooperating locking tabs formed in the body of the shingle adjacent the rear edge and spaced inwardly of the edges of the shingle, and ribs extending across the shingle parallel to the forward edge.

2. An interlocking shingle as defined in claim 1, and a down-turned flange at the lower transverse edge of the shingle, said flange having a notch therein to receive one of the parallel ribs.

3. An interlocking shingle as defined in claim 2, said notch being of the same height as the height 35 of the parallel ribs.

DAVID B. RONZONE.
